UNITED STATES PATENT OFFICE.

RUDOLF WAGNER, OF HAMBURG, GERMANY, ASSIGNOR TO THE SUPERHEATER COMPANY, OF NEW YORK, N. Y., A CORPORATION OF DELAWARE.

AIR-COOLED CONDENSATION APPARATUS FOR LOCOMOTIVES.

Application filed March 3, 1924. Serial No. 696,463.

To all whom it may concern:

Be it known that I, RUDOLF WAGNER, a citizen of the Republic of Germany, residing at Hamburg, 105 Bismarckstrasse, Germany, have invented certain new and useful Improvements in Air-Cooled Condensation Apparatus for Locomotives, for which I filed an application for patent in Germany on December 22, 1921, and of which the following is a specification.

My invention relates to air-cooled condensation apparatus for locomotives or the like, and especially to the manner of accommodating this apparatus in a locomotive.

The object of the invention is to solve the double problem which arises in steam locomotives driven by turbines and having the air-cooled condensers or coolers for the injection of cooling water arranged in front of the boiler installation in the normal direction of travel. This problem involves the difficulty of taking in a sufficient quantity of air without making the dimensions of the condensing apparatus exceed the prescribed cross-section of the railway or without obstructing the free outlook over the track from the driver's position. It further involves the difficulty of accommodating the necessary relatively large cooling surface in such a manner that sufficient air is furnished to said cooling surface while at the same time insuring that the air resistance will be moderate. With the arrangements hitherto proposed and mostly taken from the art of motor cars or air ships and the like it is not possible to overcome these difficulties.

In order to satisfy the above requirements, the area available at the front end of the locomotive is utilized for the reception of as large a volume of air as possible by causing the latter to enter through an aperture which is for the most part unobstructed, i. e., not occupied by cooling elements, in addition to which the velocity imparted to the air over this cross-sectional area by the movement of the vehicle may be increased, if desired, by any suitable form of blower, as, for example, one or more air propellers. This aperture is located at the front of a channel, the walls of which converge inwardly for a short distance and lead into a chamber of greater volume than said channel. This chamber is defined by the walls of the locomotive body or shell and has its side wall

portions open to the atmosphere, the cooling or condensing surfaces being located in the open side walls. The condensers are thus disposed in a position where the air moves at the desired lower velocity and therefore with a small air resistance, while in addition the outward air currents due to the velocity of the vehicle exercise a certain amount of suction action, thereby assisting the movement of the air.

In the drawing some embodiments of the invention are shown by way of example. Fig. 1 shows a longitudinal elevation, Fig. 2 a plan and Fig. 3 a front elevation respectively of one form of embodiment of the invention; Fig. 4 is a cross section of the cooling apparatus of a modification and Fig. 5 is a front elevation of a further modified form.

In the Figures 1 to 3 a special example of the condenser arrangement is shown for a locomotive in which a turbo-electric drive is provided for the driving wheels, in conjunction with an indirect withdrawal of the heat of the steam by a jet or water-cooled surface condenser and the use of a single air propeller in the front inlet aperture. Such a construction is shown in my co-pending application Serial No. 676,453, filed November 22, 1923.

According to this example, the reference number 40 denotes the common enclosing body for the power and cooling installation, 41 the driving wheels, 42 the electric motors driving them, 43 a high-pressure water-tube boiler equipped with a suitable superheater, 44, and air pre-heater, 45, and adapted for use with oil or pulverized coal; 46 is the inlet duct for the boiler combustion air, 47 the combustion chamber, 48 an electric generator, 49 a high-pressure turbine, 50 a low-pressure turbine, 51 a suitable transmission gear common to both these turbines, 52 a jet or water-cooled surface condenser, 53 a re-cooler for the injection or cooling water used in the condenser 52, 54 the front air inlet, 55 an air propeller, 56 the motor driving it, for example, a small turbine with the necessary transmission. Further, 57 are guides for the air between the individual groups of coolers, 58 a front bearing for the air propeller shaft, 59 the outlet duct for the hot gases, and 60 tanks for the fuel or water. The re-cooler 53, as shown, comprises a pair of radiators arranged, preferably in par-

allel, one on each side of the locomotive and adjacent to the front thereof. These re-coolers are connected as by the pipe lines indicated diagrammatically at 53^a and 53^b with the pump 53^c and condenser 52 respectively. The pump 53^c draws the condensate from the bottom of the condenser and forces it through the re-cooler from which the cooled water is carried by the pipe 53^b back 10 to the condenser.

In the arrangement shown, the boiler combustion air duct, 46, is shown as a pipe having its front end extending into the chamber behind the front air inlet 54, so that 15 the forward travel of the locomotive will tend to produce an increased draft for the boiler.

Figure 4 shows in cross-section through the cooling devices a modification according 20 to which the surface cooling in the cooler, 53, is assisted by rose sprays, 61, a part of the injection or cooling water being thereby finely divided and further cooled by partial evaporation. In this arrangement a 25 certain loss of water occurs which has to be replaced from the tanks provided. On the other hand, there is the advantage that either a larger power can be obtained with the given air inlet, 54, and the cooler, 53, 30 or the aperture, 54, can be smaller for a given power.

In Figure 5, a further modification is shown in front view in which, with the object of decreasing the height of the inlet 35 aperture, 54, the latter is flattened above and below and two air propellers, 55, are arranged therein.

In addition to the examples described, the invention can be carried out or arranged 40 in other ways, for example, other types of water-tube boiler, turbine and transmission gear, condenser or cooler, transmission gear to the driving wheels and so forth, can be employed without departing from the scope 45 of the invention, while instead of oil or pulverized coal, it is obvious that the ordinary coal firing on a grate can be used; or instead of the boiler described with only 50 one transverse upper and lower drum and one group of tubes, any other of the usual types for locomotives may be used. Further, in the case of locomotives in which the power, and quantity of steam to be condensed, 55 are not too great, some of the condenser or cooling elements could be arranged in the air inlet aperture, 54, in order to decrease the length or height of the side condensers or coolers, and so forth.

In some cases it may be advisable to condense the steam at a pressure above the ordinary condenser pressure and approximately 60 equal to atmospheric pressure or even higher, while, for example, in the case of stationary condensing steam power plants the condenser frequently works with a vacuum of

about 80 to 90%. In this case the surface condenser or cooler can be made considerably smaller than when working with a high vacuum. Further the temperature of the cooled air is higher and consequently more 70 suitable for many purposes, such, for example, as heating interiors or for drying.

In all forms of my invention, it will be understood that, as shown in Figs. 1 and 2, the channel leading to the front aperture 75 decreases gradually in cross sectional area and communicates directly with a chamber having a greater volume. By this construction, a Venturi effect is produced upon the cooling air currents which results in the 80 admission of a great volume of air, which volume of air is further increased by the suction effect of the outside air rushing past the sides of the shell of the locomotive. It will also be understood that in all forms of 85 my invention and as clearly shown in Figs. 1 and 2, the combined area of the effective openings for the outlet of the cooling air is much greater than the area of the inlet aperture 54, whereby a decrease in the velocity of the air currents is obtained at the 90 places where the air currents sweep across the cooling surface.

I claim:—

1. In a condensing system for steam locomotives, an enclosing shell or body defining a chamber located adjacent to the front of said locomotive, said shell being provided at the front thereof with an unobstructed aperture in communication with said chamber, 100 whereby the forward travel of the locomotive will cause a current of cooling air to be forced into said chamber, and the side walls of said shell being provided with apertures communicating with said chamber whereby the outside air currents due to the motion of said locomotive will produce a suction effect upon the air passing through said front aperture to said chamber, and a condenser located within said 110 chamber adjacent to said side apertures.

2. In a condensing system for steam locomotives, an enclosing shell or body defining a chamber located adjacent to the front of said locomotive, said shell being provided at the front thereof with an unobstructed aperture in communication with said chamber, whereby the forward travel of the locomotive will cause a current of cooling air to be forced into said chamber and the side walls of said shell being provided with apertures communicating with said chamber whereby the outside air currents due to the motion of said locomotive will produce a suction effect upon the air passing through said front aperture to said chamber, a condenser located within said chamber adjacent to said side apertures, and guiding vanes adjacent to said condenser and side apertures to direct the air currents therethrough.

3. In a condensing system for steam locomotives, an enclosing shell or body defining a chamber located adjacent to the front of said locomotive, said shell being provided at the front thereof with an unobstructed aperture in communication with said chamber, whereby the forward travel of the locomotive will cause a current of cooling air to be forced into said chamber, and the side walls of said shell being provided with apertures communicating with said chamber whereby the outside air currents due to the motion of said locomotive will produce a suction effect upon the air passing through said front aperture to said chamber, a condenser located within said chamber adjacent to said side apertures, and means located adjacent to said front aperture for forcing air into said chamber.
4. In a condensing system for steam locomotives, an enclosing shell or body located adjacent to the front of said locomotive, said shell being provided at the front thereof with an unobstructed aperture, a frustro-conical shaped channel leading from said aperture to said chamber and having the side walls thereof converging towards said chamber, and said chamber being of greater cross sectional area than said channel, whereby a Venturi effect will be produced upon the air forced into said aperture and channel by the forward motion of said locomotive, said shell having its side walls provided with apertures communicating with said chamber and a condenser located within said chamber adjacent to said side apertures.
5. In a condensing system for steam locomotives, an enclosing shell or body provided with a chamber having inlet and outlet apertures in communication with said chamber and arranged to cause a cooling current of air to be forced through said chamber by the forward travel of said locomotive, the effective cross sectional area of said outlet apertures being greater than said front aperture, whereby the velocity of the cooling air current adjacent to said outlet apertures will be less than at said inlet, and a condenser within said chamber adjacent to said outlet apertures.
6. In a condensing system for steam locomotives, an enclosing shell or body defining a chamber located adjacent to the front of said locomotive, said shell being provided at the front thereof with an unobstructed aperture in communication with said chamber, whereby the forward travel of the locomotive will cause a current of cooling air to be forced into said chamber, and the side walls of said shell being provided with apertures communicating with said chamber whereby the outside air currents due to the motion of said locomotive will produce a suction effect upon the air passing through said front aperture to said chamber, a condenser located within said chamber adjacent to said side apertures, and means connecting the boiler of said locomotive with said chamber to divert a portion of the air from said chamber to said boiler for combustion air.
7. The method of working a locomotive steam turbine installation having a condensing apparatus arranged in front of the boiler installation (in the normal direction of travel) and along the sides of the locomotive, consisting in condensing the exhaust steam of the steam turbine at a pressure above the usual condensing pressure and not less than atmospheric pressure.
- In testimony whereof I have hereunto set my hand.

RUDOLF WAGNER.
